UNITED STATES PATENT OFFICE.

FRANK J. JOHNSON, OF HARTFORD, CONNECTICUT.

COMBINED STEAM AND HOT-WATER HEATER.

SPECIFICATION forming part of Letters Patent No. 681,226, dated August 27, 1901.

Application filed April 20, 1901. Serial No. 56,726. (No model.)

To all whom it may concern:

Be it known that I, FRANK J. JOHNSON, a citizen of the United States, residing in Hartford, in the county of Hartford and State of Connecticut, have invented certain new and useful Improvements in a Combined Steam and Hot-Water Heater, of which the following is a specification.

My invention relates to a combined hot-water and steam heater; and it has for its object the provision of means whereby the ordinary boiler now in use for steam-heating purposes only may be so divided that it may be utilized both as a steam-heater and a hot-water heater.

In the sectional steam-boiler now employed the sections or manifolds thereof are connected in assembling the boiler by through-bolts, and in the steam-dome of the boiler and at its lower part these manifolds are made to communicate with each other by what are known in the trade as "push-nipples," which are castings or fixtures connecting one manifold with another manifold in order to afford free steam and water connection between all of the sections of which the boiler is composed.

It frequently happens that it is desirable to employ steam for heating one part of a building and hot water for heating another part of said building; and my invention is designed particularly for enabling both the steam and hot-water systems to be utilized, as desired, in the same building and with but the use of a single boiler.

My invention may be carried into effect in many ways, and the main object thereof is to so divide steam-boilers of various kinds now in use that one part of the boiler may be utilized as a steam-heater and the other part thereof as a hot-water heater.

In carrying out the invention I may employ a set of push-nipples, having diaphragms or partitions for dividing the boiler into sections, or what are known as "blind" sections or manifolds may be employed, or a manifold dividing the boiler into the desired sections, said manifold having a longitudinal partition for accomplishing the same purpose, may be employed, the invention not being limited to any specific device for carrying it into effect.

In the accompanying drawings, Figure 1 is a side elevation of a boiler of common construction to which one form of my invention is applied. Fig. 2 is a transverse section taken on line xx , Fig. 1, looking in the direction of the arrow. Fig. 3 is a vertical section of one of my improved push-nipples. Fig. 4 is a side elevation of the improved push-nipples. Fig. 5 is a detail view, partially in section, of a modification in which a blind section or manifold is employed; and Fig. 6 is a view similar to Fig. 5, representing another modification in which one of the sections or manifolds is provided with a longitudinal diaphragm or partition.

Like characters designate similar parts throughout the several views.

Referring to the drawings, the numeral 10 designates a common form of sectional steam-boiler to which my invention is shown applied, and the numerals 12 the manifolds or sections which are united by longitudinal rods or bolts 13 in assembling the boiler. 75 These manifolds are hollow to afford a circulation of the water employed for generating steam, and the apparatus is provided with a steam-dome 14 with lateral pipes 15 and with a vertical pipe 16 for containing water. A 80 water-supply pipe 17, containing a valve 17', by which the entrance of water is regulated, and the usual return-pipe 18 will also be found illustrated in Figs. 1 and 2.

Designated by the numeral 19 is an improved form of push-nipple, which serves to divide the heating apparatus illustrated into sections A and B, respectively, the section A serving as a steam-heater and the section B as a hot-water heater. These push-nipples are each provided with a diaphragm 19', and when placed in the openings provided for their reception in the sections or manifolds 12, as illustrated in Figs. 1 and 2, serve to divide the apparatus into the two compartments A and B, respectively, above specified, in the former of which steam is generated for the purpose of heating by that agent and in the latter of which hot water is relied upon as the heating agent.

Connected to the hot-water section B of the apparatus are the usual supply and return pipes 22 and 23, respectively, and leading from both sections of said apparatus are pipes

24 and 25, respectively, for supplying steam and hot water to the parts of the building desired.

5 While nipples of a particular kind are illustrated, it is distinctly to be understood that the invention is not limited to the form of nipple shown, for other forms containing a diaphragm or partition may be employed as substitutes without departure from the scope 10 thereof.

The usual grate 26 for receiving fuel is illustrated in Fig. 2, and the products of combustion emerge from the apparatus through the flue 27 and pipe 28, leading to the chimney.

15 In Fig. 5 I have illustrated a modification in which the push-nipples, with diaphragms, are dispensed with, and what is termed a "blind" section or manifold 29 is inserted between two of the manifolds 12 for the purpose 20 of dividing off or separating one of the sections of the apparatus from the other.

25 In the modification illustrated by Fig. 6 a section or manifold 30, having a longitudinal partition 31, is employed for effecting the same purpose.

30 Push-nipples 32 of ordinary form are illustrated in the several views for connecting the steam-dome of one section of the apparatus with the various manifolds in the section A, and similar push-nipples are also employed for permitting a circulation of the hot water 35 in the section B, as illustrated in Fig. 1.

35 It frequently happens that it is deemed necessary or desirable to utilize one section of the apparatus for steam - heating purposes and the other section for hot-water heating, as above stated, and by dividing the boiler in the manner set forth I am enabled to accomplish these results with ease and facility.

40 While the invention is shown on a type of apparatus in which the sections or manifolds are arranged vertically, it is distinctly to be understood that it is not limited thereto, for it may be employed with various forms of 45 boilers now on the market, whether of the vertical, horizontal, or other types, or with sections cast solid.

50 The blind nipples 19 containing the diaphragms or partitions 19' may be applied to any section of the boiler required without departure from the invention, and either the rear or front section of said boiler may be utilized as the hot-water section or the steam-section, if desired.

55 Having thus described my invention, what I claim is—

1. In a heating apparatus, the combination, with a boiler, of closed nipples for dividing said boiler into sections, one of said sections 60 to be utilized for generating steam for a steam-heating system, and the other of said sections as a means for supplying hot water to a hot-water heating system.

65 2. The combination, with a boiler composed of separate sections, of closed nipples for dividing said sections so that one part of the boiler may be utilized as a steam-heater

and the other part of said boiler as a hot-water heater.

3. In an apparatus of the class specified, 70 the combination, with a boiler composed of sections or manifolds, of means for uniting said manifolds; and closed push-nipples for separating a part of said manifolds from another part thereof.

75 4. The combination, with a boiler composed of tubular sections or manifolds, each of said manifolds having a series of openings, of means for connecting one manifold with another manifold, to permit a circulation of 80 the heating agent; and closed push-nipples for dividing off one set of manifolds from another set, whereby the boiler is separated into sections, one of which may be employed 85 as a steam-heater and the other as a hot-water heater.

5. The combination, with a boiler composed of manifolds perforated at different points to permit a circulation of the heating agent, of open nipples inserted in said perforation; and means located between two opposing open nipples for dividing said boiler 90 into sections, whereby one part of the boiler may be utilized as a steam-heater and the other part thereof as a hot-water heater. 95

6. The combination, with a boiler composed of sets of manifolds, of means for uniting said manifolds; means for connecting the manifolds to afford a circulation of the heating agent; and closed nipples for dividing one 100 set of manifolds from another set, so that the sections of the boiler may be utilized for different purposes.

7. The combination, with a boiler composed of sections, of closed nipples for uniting said sections; means for separating one section from another section, and supply and return pipes connected with each section.

8. The combination, with a boiler composed of tubular manifolds, of a set of nipples for connecting these manifolds at different points; and a set of "blind" nipples for dividing the boiler into sections, one section to be employed as a hot-water heater and the other section as a steam-heater; and supply 115 and return pipes for both sections.

9. The combination, with a boiler composed of manifolds, of open nipples uniting certain of said manifolds at different points; and closed or "blind" nipples dividing one 120 set of manifolds from another set of manifolds.

10. In a combined steam and hot-water boiler the combination, with manifolds having openings at their upper ends and other 125 openings in their lower ends; of "push-nipples" connecting one manifold with another, and located in said openings; and "push-nipples" having diaphragms located in the openings of two adjacent manifolds, and serving 130 to separate one set of manifolds from another set, thereby to divide the boiler into sections for utilization as steam and hot-water heaters.

11. The combination, with a series of ver-

tical manifolds, of hollow nipples uniting some of said manifolds; and partitions between one set of manifolds and another set of manifolds for dividing the boiler into sections, said partitions being located between opposing hollow nipples.

5 12. In an apparatus of the class specified, the combination, with a boiler composed of

tubular sections, each section having an opening for the passage of water, of a partition adapted to be located between the opposing openings, substantially as specified.

FRANK J. JOHNSON.
